UNITED STATES PATENT OFFICE.

WILLIAM J. McILVANE, OF NEW YORK, N. Y.

POST ANCHOR.

Application filed October 12, 1925. Serial No. 61,937.

The object of the present invention is to provide a post anchor whereby posts and the like, for example telephone, telegraph and power poles may be securely anchored to the ground, by means which shall not require digging holes for the reception of any one of the anchor units, each unit being applied by driving the same directly into the earth. A further object of the invention is to so construct the primary units of the anchor in such manner that although they are separately driven into the earth, they become securely interlocked together in use, and have no relative movement.

15 The invention will be understood by reference to the accompanying drawing, in which—

Figure 1 is a sectional side elevation of the assembled anchor in operative position; 20 Figure 2 is an elevation of the anchor blade showing in fragmentary section certain elements used in applying or withdrawing the same, and

Figure 3 is a sectional side elevation on the line 3—3, Figure 2;

Figure 4 is a plan view of the anchor blade;

Figure 5 is a diagrammatic sectional view showing the guy rod head in operative engagement with the blade, and

Figure 6 is a plan view of the guy rod head.

Referring to the drawings, 1 is an anchor blade, roughly rectangular in form and at 35 its lower end provided with the forks 1^x and a central longitudinal slot 2. The surface of the blade surrounding the slot is formed with projecting teeth 2^x which are designed to interlock with the teeth of the guy rod head as later to be explained.

In the present embodiment of the invention, the anchor blade is formed with a square head 3^x which is formed with a threaded aperture 4. Aperture 4 is designed 45 to receive the lower threaded end of a rod 5 by means of which the blade may be withdrawn from the earth, if desired, without the necessity of digging.

The second primary member of the anchor comprises guy rod head 6 which is formed with a pointed lower end 6^x and an enlarged rear portion, the upper surface of which is toothed at 7 in a manner corresponding to the toothed portion 2^x of the blade. The guy rod head 6 is formed with a threaded axial aperture 8 to receive the

guy rod 9, and the rod at its upper end may be formed with suitable means for attachment to the guy or strut cable 10.

It is not essential in practice that the blade 60 and anchor head be provided with surface interlocking means, but the provision of such means is desirable because it prevents relative movement between the two units and results in a more efficient anchoring of the 65 guy cable.

In the operation of the device, the anchor head is first driven into the earth at an angle extending in the same angular line in which it is desired to anchor the guy cable. I have 70 found it desirable to drive the head at a 45° angle, or substantially in the angle illustrated in Figure 1 of the drawings.

After the head has been driven to the desired depth, the anchor blade is driven into 75 the ground in a line extending transversely of the guy rod and preferably at substantially the same angular degree. The blows of the driving mallet fall upon the top of tubular member 11 and are thrown upon that 80 portion of the blade surrounding its head 3^x. The blade will be driven until its forks 1^x embrace the guy rod. If the blade has been driven slightly out of line so that the guy rod is not directly opposite the slot 2, continued downward movement of the blade 85 will cause the inwardly inclined edges of the blade to so mutually adjust the positions of the rod and blade that the rod will finally be caused to enter slot 2. In practice the 90 blade is driven at such an angle as to initially embrace the guy rod at a point slightly above the head 6, and the subsequent tension of the guy cable 10 and strain upon the guy rod and head will cause the latter to contact with the side wall of the blade and cause 95 the teeth to interlock.

After the driving of the blade is completed, tubular member 11 may be withdrawn and also rod 5 if desired, or the rod 100 may be left in place to enable withdrawal of the blade without digging down to the latter.

The relative angles at which the rod and blade are driven to secure the best efficiency 105 may be determined in advance. For example, if the anchor head is driven at a 45° angle with relation to the ground line, and the guy rod is 6 feet long, then the distance between the ground surface point at which the head is driven and the ground surface 110 point at which the blade should be driven is

8 feet, 5 inches, the blade being preferably driven at an angle of 45° relative to the ground line. The distance between the driving points for the anchor head and blade will vary with the length of the guy rod and the angle at which it is driven.

Having described my invention what I claim and desire to secure by Letters Patent is as follows:

10 A land anchor comprising a guy rod hav-

ing a pointed head and adapted to be driven into the ground, and a blade adapted to be driven into the ground independently of the rod and at an angle thereto for engagement with said head, the blade having a forked end adapted to embrace the rod. 15

In testimony whereof, I have signed my name to this specification.

WILLIAM J. McILVANE
